UNITED STATES PATENT OFFICE.

BERNARD M. BERNGARTT AND MAURICE M. BERNGARTT, OF BALTIMORE, MARYLAND.

DUST CAP FOR VALVE STEMS.

Application filed March 17, 1921. Serial No. 452,975.

To all whom it may concern:

Be it known that we, BERNARD M. BERNGARTT and MAURICE M. BERNGARTT, citizens of the United States, residing at Baltimore, in the county of Baltimore City, State of Maryland, have invented certain new and useful Improvements in Dust Caps for Valve Stems; and we do hereby declare the following to be a full, clear, and exact description of the invention, such as will enable others skilled in the art to which it appertains to make and use the same.

This invention relates to new and useful improvements in dust caps for the valve stems of pneumatic tires.

As is well known, the valve stem of the air tube of a tire is exteriorly threaded for the reception of a cap that is ordinarily screwed down over the stem until its lower edge impinges tightly against a dust washer, moisture and other foreign matter from entering the shoe by way of the opening in the felly through which the valve stem projects. The placing and removal of this dust cap however, is extremely tedious and as a result, the dust cap is often omitted and its well known benefits are lost.

It is the object of the present invention to provide a structure in which the dust cap may be applied and removed by very slight manipulation, but yet will be held securely when in place.

In the drawing:

Figure 1 is a view in which the ring that is carried by the felly is provided with bayonet slots to receive inwardly directed pins on the cap, to hold the latter in position.

Figure 2 is a section on the line 2—2 of Figure 1.

Figure 3 is a section on the line 3—3 of Figure 2.

Referring particularly to the accompanying drawings, there is shown a metal felly 10 on which is mounted, in any desired manner, a tire shoe 11, that encloses an air tube 12, having a valve stem 13 of ordinary construction, projecting through the opening 14, in the felly.

Secured on the felly, and surrounding the valve stem 13, is a metal ring 65 having the L-shaped grooves 66 in its peripheral face, the vertical portion of each of which extends through the upper face of the ring 65. The dust cap 67 is of the general or common form, but instead of

having interior threads for engagement with the threads of the valve stem 13, the lower end of the cap is provided with the inwardly extending pins 68 which move downwardly through the vertical portions of the L-shaped grooves 66, and thence circularly of the ring 65, into the horizontal portions of the grooves, when the cap is rotated.

Secured within the inner end wall of the horizontal portion of each of the grooves 66, is the bight portion of a substantially U-shaped spring member 69, the legs 68' of which extend to a point in a vertical line with the inner wall of the vertical portion of the groove. The intermediate portions of the legs 68' are outwardly bowed, as indicated at 69', for the pin 68 of the cap.

The free ends of the legs 68' are sufficiently separated to permit the ready entrance of the pin 68, when said pin is moved from the vertical portion of the groove into the horizontal portion, said pin springing the legs apart, and permitting the pin to snap into the bowed portions 69'.

While the legs 68' are of sufficient strength to prevent accidental displacement of the pins 68, a turning movement of the cap in the opposite direction, will readily cause the pins to slip from the legs, and engaging against the outer wall of the vertical portion of the groove, permit the ready removal of the cap.

What is claimed is:

1. The combination with a wheel rim and a valve stem projecting therethrough, of a ring secured on the rim and surrounding the valve stem, the ring having L-shaped grooves in its peripheral face, a cap embracing the ring, pins on the cap engaging in the grooves, and opposing resilient jaws mounted in each of said grooves for releasably receiving said pins.

2. The combination with a wheel rim and the valve stem protruding therethrough, of a ring secured to the rim and encircling the valve stem, the ring having L-shaped grooves in its peripheral face, spring gripping jaws in each of the grooves, a dust cap engaged over the valve stem and enclosing the said ring, and inwardly directed pins on the ring enclosing end of the cap for engagement in said grooves and engagement between said spring jaws.

3. The combination with a wheel rim, of a ring secured thereto and having L-shaped

grooves in its peripheral face, a pair of spring jaws secured in the inner end wall of the horizontal portion of each of the grooves and having the arms thereof oppositely bowed, intermediate their lengths, and terminating at the inner wall of the vertical portion of the groove, a cap enclosing the ring and having inwardly directed pins releasably engaged in the grooves and

within the bowed portions of the spring 10 jaws.

In testimony whereof, we affix our signatures, in the presence of two witnesses.

BERNARD M. BERNGARTT.
MAURICE M. BERNGARTT.
